FLUSH TANK VALVE

Arthur N. Asselin, Fall River, Mass.

Application February 1, 1939, Serial No. 254,093

6 Claims. (Cl. 137—104)

The invention relates to a float operated valve and more especially to flush tank supply valves.

The primary object of the invention is the provision of a valve of this character, wherein the same is controlled by a float and is held against sticking to its seat with resultant positive action, both for the opening and closing of such valve, and thereby regulating the supply of water to a flush tank box, the shutting off of the water thereto being had in the direction of the inflow and the higher the pressure the tighter the said valve will close and the quicker the tank will be filled.

Another object of the invention is the provision of a valve of this character, wherein the action of the valve is positive and sensitive in that sufficient power is had from the water pressure flowing into a flush tank or box to assure the perfect working of the valve and with minimum lifting action upon the float, the valve being quick closing and thus shutting off instantly the inflow of water when the pressure thereof is at the highest peak.

A further object of the invention is the provision of a valve of this character, wherein the parts thereof are readily accessible and of a minimum number, thereby providing for easy repairs and replacement of parts and maximum life.

A still further object of the invention is the provision of a valve of this character, wherein the valve assembly and the float assembly are of novel construction to assure quick action of the valve and the perfect working thereof on installation within a flush tank or box.

A still further object of the invention is the provision of a valve of this character, which is simple in its construction, thoroughly reliable and efficient in operation, being possessed of few parts resulting in durability thereof and elimination of repairs and replacements, strong, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a vertical sectional view through the valve constructed in accordance with the invention.

Figure 2 is a top plan view thereof.

Figure 3 is a sectional view taken on the line

3—3 of Figure 1 looking in the direction of the arrows.

Similar reference characters indicate corresponding parts throughout the several views in the drawing.

Referring to the drawing in detail, the valve constituting the present invention comprises a substantially T-shaped valve casing or shell 10 having a water inlet passage 11 to which is common the inlet nipples 12 and 13, respectively, 10 these being preferably at right angles to each other so that the valve casing or shell 10 can be mounted for the inflow of water into a high or low flush tank or box. The selected nipple 12 or 13 is united with the water supply pipe or lead and the other being closed by a plug 14, which is interchangeable to either of the said nipples. Removably fitted within the passage 11 is a valve cage or sleeve 15, being held in place by a locking ring or collar 16 and with which communicates 20 the discharge filling pipe 17 for the tank or box (not shown) and only a portion of this tube or pipe 17 being disclosed. Also communicating with the said valve cage or sleeve 15 is a refill or siphoning tube or pipe 18, for the conventional 25 purpose of supplying water to a toilet bowl (not shown).

At the end innermost in the passage 11 of the cage 15 is a valve seat 19 for a slidable valve 20 movably fitting the cage 15 and this valve controls the water from the passage 11 passing to the tubes or pipes 17 and 18, being engageable with the seat 19 for shutting off the flow of water.

Formed on the casing or shell 10 at the uppermost side are the bearings 21 and 22, respectively. 35 The bearing 21 pivotally supports a rocking lever 23, the pivot being indicated at 24, and this lever has the arm 25 supporting a weight 26. The bearing 22 has pivotally connected thereto toggle linkage 27, which is also pivoted to the lever 23, 40 the pivots being indicated at 28 and 29, respectively. Swingable upon the pivot 24 for the lever 23 is a float arm 30 which has adjustably fitted thereto the hanger stem 31 of a float 32, being suitably weighted at 33, the adjustability of the 45 hanger arm being had by a set screw 34 fitting the float arm 30. This arm is formed with a forked end providing spread extensions 35 and 36, respectively, each having the lateral pins 37, the one on the extension 35 being in overhanging 50 relation to the toggle linkage 27, while the pin 37 on the extension 36 is disposed beneath this toggle linkage. The rise of the float 32 with the rise of the water supply within the tank or box causes the float arm 30 to swing counter-clock- 55

wise as viewed in Figure 1 and the pin 37 on the extension 35 of this arm actuates the toggle linkage so that the valve 20 will be shifted to shut-off or closing position, the lever 23 being 5 operably attached to the valve 20 through the forked formation 38 in said lever and the coupling pin 39, respectively, on the valve. The weight 33 on the float 32 is for partially sinking the float within water supplied within the tank 10 or box so that when the water is discharged from the said tank or box this float will drop, rocking the weighted arm 30, forcing the pin 37 on the extension 36 in the direction of the toggle linkage 27 for action thereon to cause the valve to be 15 moved away from the seat 19 therefor to an open position permitting the water through the passage 11 and the pipe 17 to fill the tank or box. After the water reaches a determined level, the float rising therewith operates the arm 30 so that 20 the pin 37 on the extension 35 will become active on the toggle linkage 27 for actuating the valve 20 moving it to a closed position and thus shutting off water supply to the tank or box. The weight 26 on the arm 25 of the lever 23 provides 25 positive closing action in the operation of the valve. The valve shuts off the water supply in the direction of the inflow through passage 11 so that the pressure of the water aids in effecting the tight fitting of the valve to its seat. In this 30 manner there is no pressure required on the float to keep the valve closed tight against its seat and the weight 33 on the float enables positive opening action of the valve and the float assures power for the closing of the valve with 35 minimum lifting power.

One of the links of the toggle linkage 27 carries a stop 40 for limiting the action of the toggle linkage in one direction so that on the upward movement the links of the said toggle are stopped 40 in horizontal alignment with each other yet not interfering with the downward breaking of the toggle linkage 27.

What is claimed is:

1. A valve of the kind described, comprising a 45 casing having a valve for controlling a flow passage therethrough, a rocking lever operating said valve, a float arm swingingly supported relative to said casing, toggle linkage connections between said lever and said casing, and extensions 50 on the arm and active against the toggle linkage connections alternately at opposite sides thereof for imparting opening and closing movements to the valve.

2. A valve of the kind described, comprising a 55 casing having a valve for controlling a flow passage therethrough, a rocking lever operating said valve, a float arm swingingly supported relative to said casing, toggle linkage connections between said lever and said casing, extensions on the arm 60 and active against the toggle linkage connections alternately at opposite sides thereof for imparting opening and closing movements to the valve,

and means limiting the movements of the linkage of the toggle connections in one direction.

3. A valve of the kind described comprising a 5 casing having an intake and a valve for controlling a passage therethrough aligned with said intake, said valve confronting the fluid admitted through the intake for assisting said valve to its seat, a rocking lever operating said valve, a toggle linkage connection between said lever and said casing, and a float arm swingingly supported relative to the casing and extending above and below the linkage connection for alternate action thereon in opposite directions.

4. A valve of the kind described comprising a 15 casing having an intake and a valve for controlling a passage therethrough aligned with said intake, said valve confronting the fluid admitted through the intake for assisting said valve to its seat, a rocking lever operating said valve, a toggle linkage connection between said lever and said 20 casing, a float arm swingingly supported relative to the casing and extending above and below the linkage connection for alternate action thereon in opposite directions, and weight means associated with the lever and disposed over the linkage 25 connection in a direction reversely to the disposition of the float arm.

5. A valve of the kind described comprising a 30 casing having an intake and a valve for controlling a passage therethrough aligned with said intake, said valve confronting the fluid admitted through the intake for assisting said valve to its seat, a rocking lever operating said valve, a toggle linkage connection between said lever and said 35 casing, a float arm swingingly supported relative to the casing and extending above and below the linkage connection for alternate action thereon in opposite directions, weight means associated with the lever and disposed over the linkage connection in a direction reversely to the disposition 40 of the float arm, and means coacting with the linkage connection to limit the movement thereof in one direction.

6. A valve of the kind described comprising a 45 casing having an intake and a valve for controlling a passage therethrough aligned with said intake, said valve confronting the fluid admitted through the intake for assisting said valve to its seat, a rocking lever operating said valve, a toggle linkage connection between said lever and said 50 casing, a float arm swingingly supported relative to the casing and extending above and below the linkage connection for alternate action thereon in opposite directions, weight means associated with the lever and disposed over the linkage 55 connection in a direction reversely to the disposition of the float arm, means coacting with the linkage connection to limit the movement thereof in one direction, and a pivotal support for both the lever and the float arm. 60

ARTHUR N. ASSELIN.
